UNITED STATES PATENT OFFICE.

JOHN B. LOTT, OF ANDERSON, INDIANA.

TRACK FOR RAILWAY-CARS AND OTHER VEHICLES.

1,011,978.

Specification of Letters Patent.

Patented Dec. 19, 1911.

Application filed August 17, 1911. Serial No. 644,710.

To all whom it may concern:

Be it known that I, JOHN B. LOTT, a citizen of the United States, resident of Anderson, in the county of Madison and State of Indiana, have made a certain new and useful Invention in Tracks for Railway-Cars and other Vehicles; and I declare the following to be a full, clear, and exact description of the same, such as will enable 10 others skilled in the art to which it appertains to make and use the invention, reference being had to the accompanying drawings, and to letters or figures of reference marked thereon, which form a part of 15 this specification.

The invention relates to tracks for street railway, interurban and other vehicles and cars having any suitable motive power, and it consists in the novel construction and 20 combinations of parts, as hereinafter set forth.

In the accompanying drawings, illustrating the invention, Figure 1 is a plan view of my invention as applied to a double track, and showing two vehicles thereupon; Fig. 2 is a cross section of the double track; Fig. 3 is a plan view of the invention as applied to a single track; and Fig. 4 is a cross section of the same.

30 The numeral 1 designates a center rail formed preferably of artificial stone, such as concrete or cement, which will have no joints, said rail being sunk in the roadbed preferably for about two-thirds of its 35 height, and having a plane top surface 2.

At the sides of the center rail, metal rails 3, 3 are provided, one at each side, to complete a double track, the central rail being of sufficient breadth to allow the inside 40 wheels of vehicles going in opposite directions to pass each other with a proper clearance.

The metal rails, which are preferably of standard character, are provided each with 45 a concrete or cement base 4, arranged longitudinally thereof, and which is also sunk in the roadbed, the rails being bolted to their cement bases by vertical bolts 5, 5, a wooden surface plate 6 and a wooden bottom 50 plate 7 being preferably used with each cement base.

Suitable means are provided to brace the rails in parallel position, such as transverse brace rods 8 engaging transverse perforations 9, 9 of the center rail and cement bases 55

of the side rails, suitable nuts 10, 10 being threaded upon the brace rods and having abutment against both sides of each of the cement bases and of the center rail. To further provide against spreading of the 60 side rails, wedge-form key extensions 11 may be provided for the cement bases thereof, said extensions being also sunk in the roadbed.

In the use of my track, the vehicle wheels 65 at the outside are designed to have a lateral flange or flanges for guiding engagement with the metal rails, this flange being preferably provided upon a supplemental tire adapted for detachable connection with a 70 vehicle wheel.

My invention is designed to reduce the expense and labor required in laying tracks, and to provide a durable and satisfactory track for motor cars and other vehicles. 75 The surface and bottom plates 6 and 7, while preferably of wood, may be of other suitable material, and are designed to act as cushions. A bottom plate 12 may be employed for the center rail 1, this plate being 80 also preferably of wood, and acting as a cushion.

In Figs. 3 and 4 of the drawings is shown a modification of the invention, as applied to a single track, the reference characters 85 being the same, and the stone rail 1^a having a plane top surface 2^a of breadth sufficient to accommodate cars and other vehicles of different gage.

Having thus described my invention, 90 what I claim as new and desire to secure by Letters Patent is:

1. A double track for railway cars and other vehicles, comprising a center rail having a foundation portion sunk in the roadbed and a plane top surface of breadth sufficient to accommodate the inside wheels of passing vehicles, and guide rails at each side adapted for use with flanged wheels. 95

2. A double track for railway cars and other vehicles, comprising a stone center rail having a foundation portion sunk in the roadbed, guide rails at each side adapted for use with flanged wheels, longitudinal bases for said guide rails, and transverse 105 bracing means.

3. A double track for railway cars and other vehicles, comprising an artificial stone central rail having a foundation portion sunk in the roadbed, metal guide rails at 110

- each side, longitudinal artificial stone bases for said guide rails, and transverse brace rods for said center rail and said bases.
4. A double track for railway cars and other vehicles, comprising an artificial stone center rail having a foundation portion sunk in the roadbed, metal guide rails at each side, longitudinal artificial stone bases for said guide rails, cushion plates for said longitudinal bases and center rail, vertical bolts for said guide rails engaging perforations of said bases and of the wooden plates, and transverse brace rods engaging perforations of said bases and of said center rail.
5. A track for railway cars and other vehicles, comprising an artificial stone rail having a foundation portion sunk in the roadbed and a plane top surface of breadth sufficient to accommodate cars and other vehicles of different gage and adapted for use with unflanged wheels, a metal guide rail adapted for use with flanged wheels, a longitudinal artificial stone base for said guide rail, cushion plates for said base and said stone rail, vertical bolts for said guide rail engaging perforations of said base and of the cushion plate thereof, and transverse brace rods engaging perforations of said base and of said stone rail.
6. A track for railway cars and other vehicles, comprising an artificial stone rail having a foundation portion sunk in the roadbed and a plane top surface of breadth sufficient to accommodate cars and other vehicles of different gage and adapted for use with unflanged wheels, a metal guide rail adapted for use with flanged wheels, a longitudinal artificial stone base for said guide rail, cushion plates for said base and said stone rail, vertical bolts for said guide rail engaging perforations of said base and of the cushion plate thereof, and transverse brace rods engaging perforations of said base and of said stone rail.

In testimony whereof I affix my signature, in presence of two witnesses.

JOHN B. LOTT.
